CLAIM

The ornamental design for an upright support column for modular furniture, as shown and described.

DESCRIPTION

FIG. 1 is a side elevational view of a upright support column for modular furniture embodying our new design;

FIG. 2 is an end elevational view thereof;

FIG. 3 is a side elevational view thereof of the opposite side from FIG. 1;

FIG. 4 is an end elevational view thereof of an end opposite from that of FIG. 2;

FIG. 5 is a top plan view thereof;

FIG. 6 is a bottom plan view thereof;

FIG. 7 is a sectional view thereof taken as on line 7—7 in FIG. 3;

FIG. 8 is a side elevational view of an upright superstructure for office desk components made according to a second embodiment of our invention;

FIG. 9 is an end elevational view thereof;

FIG. 10 is a side elevational view thereof taken from a side opposite from FIG. 8;

FIG. 11 is an end elevational view thereof showing an end opposite that shown in FIG. 9;

FIG. 12 is a top plan view thereof;

FIG. 13 is a bottom plan view thereof; and,

FIG. 14 is a sectional view taken as on line 14—14 in FIG. 10.
